TIMER

Ethlyn B. Gaylord, Temple City, Calif.

Application March 10, 1952, Serial No. 18,839

Term of patent 3½ years

(Cl. D42—7)

To all whom it may concern:

Be it known that I, Ethlyn B. Gaylord, a citizen of the United States and a resident of Temple City, California, have invented a new, original, and ornamental Design for a Timer, of which the following is a specification, reference being had to the accompanying drawing which forms a part of said specification, and in which drawing:

Fig. 1 is a front elevation of a timer embodying my new design;

Fig. 2 is an elevational view of the right hand side of the timer shown in Fig. 1;

Fig. 3 is a top plan view, and

Fig. 4 is an elevational view of the left hand side of Fig. 1.

Portions of the figures are lined for color.

I claim:

The ornamental design for a timer, substantially as shown and described.

ETHLYN B. GAYLORD.
